UNITED STATES PATENT OFFICE.

PHILLIPS THOMAS, OF EDGEWOOD, PENNSYLVANIA, ASSIGNOR TO WESTINGHOUSE ELECTRIC & MANUFACTURING COMPANY, A CORPORATION OF PENNSYLVANIA.

GLOW-DISCHARGE TRANSMITTER.

Application filed November 14, 1922. Serial No. 600,822.

My invention relates to telephone systems and apparatus, having particular relation to sound-wave translating devices.

Broadly speaking, an important object of my invention is to provide a translating device adapted to effect an energy interchange between a fluid medium subject to vibratory motion and an electrical circuit carrying vibratory electrical currents.

More specifically, an object of my invention is to provide a translating device of the class described, wherein sound waves are faithfully translated into correspondingly modulated electrical energy without impairing the quality, tone and quantity of the translated energy.

Another object of my invention is to provide a translating device of the class described above which is characterized by its simplicity of design and operation and which lends itself to inexpensive quantity production methods of manufacture and wherein the several parts may easily be made by existing automatic machinery and may readily be assembled with a minimum expenditure of time and money.

A further object of my invention is to provide an improved translating device of the glow-discharge type wherein the intensity of response to pressure variations is independent of the frequency of such variations.

A still further object of my invention is to provide a glow-discharge translating device which is unaffected by drafts of air currents and which remains permanently in a sensitive state.

A glow discharge which is established between spaced positive and negative electrodes may comprise the following portions: a positive or anode column, which is in immediate contact with the positive electrode; a Faraday dark space; a negative light; a cathode dark space; and a cathode glow which is in immediate contact with the negative electrode. As a result of considerable experimental work, I have found that the sensitivity of the portion of the discharge including the positive column varies with the frequency of impinging sound waves and that the sensitivity of the remaining portions of the discharge, including the Faraday dark space, the cathode glow, the cathode dark space and the nega-

tive light, is substantially constant for pressure variations of all frequencies.

In the practice of my invention, I provide an amplifying or translating system which is responsive to only such variations in the voltage-current characteristic of the discharge as are included in the portion of the discharge between the end of the positive column and the negative electrode. The desired result may be accomplished by employing a three-electrode translating device, the input terminals of which are connected, respectively, to the negative discharge electrode and to a third electrode which is positioned in the discharge immediately adjacent to the end of the positive column. The third electrode is provided with an aperture through which the end of the positive column extends, as will be more specifically described hereinafter.

I have further found that the quality of the translated energy, as well as the stability of the discharge in the presence of air currents, is greatly improved by shielding the anode column from sound waves during the normal operation of my device, as will be explained more fully hereinafter.

Other objects and applications of my invention, as well as details of construction and operation whereby my invention may be practiced, will be apparent from the following description, when taken in connection with the accompanying drawing, wherein:

Figure 1 is a diagrammatic view of circuits and apparatus embodying my invention;

Figure 2 is a greatly enlarged detail view of the discharge electrodes of Fig. 1, together with a third electrode and means for shielding the anode column.

In one form of embodiment of my invention shown in the drawing, a pair of copper electrodes 1 and 2, having spaced sparking tips 3 and 4, respectively, terminating in fine points, are connected by conductors 5 and 6, respectively, to the plus and minus terminals of a source of direct-current energy (not shown). The sparking tips 3 and 4 are preferably made of copper because of the fact that a glow discharge may be easily established and readily maintained between electrodes of such material and because the discharge once established is extremely quiet

in operation, in comparison with other well known materials where in some cases it is even impossible to establish a glow discharge. For instance, so far, it has been found impossible to establish a glow discharge between electrodes of manganese, iron, nickel, carbon, aluminum or molybdenum, while the discharge, which was established between tungsten, silver and platinum electrodes was exceedingly noisy.

10 A resistor 7 is connected in series-circuit relation to the conductor 5 and serves to maintain the currents through the discharge substantially constant, notwithstanding variations in the characteristic of the discharge with pressure, all as hereinafter described. In the particular system employed during experimental work, the energy source (not shown) had an electromotive force on the order of 6000 volts, and the resistance of the resistor 7 was on the order of a megohm.

When the electrodes are separated, say $\frac{1}{16}$ of an inch for a system having the constants just mentioned, a discharge is established between the two electrodes 1 and 2, which differs from the ordinary arc-type of discharge, in the following important respects: the electrodes are relatively cool; there is substantially no vaporization or melting or burning of the electrodes; the customary hot-spot characteristic of the ordinary arc is absent; and the discharge, when formed between certain materials, as copper, takes place in a steady smooth and unfluctuating manner.

35 The latter operating characteristic of the glow discharge is of special importance inasmuch as fluctuations in the operation of the discharge may be such as to cause potential or current variations which are comparable, in magnitude, to the variations caused by sound waves, as will be apparent in the light of the following description.

The glow discharge which is established between the electrodes 1 and 2 comprises the 45 following portions arranged in their respective order between the negative electrode 2 and the positive electrode 1; namely, a cathode glow 8, which is in immediate contact with the negative electrode 2, a cathode dark space 9, also known as Crooke's dark space, a negative light 11; a Faraday dark space 12, and a positive column 13, which terminates on the tip 3 of the positive electrode 1, all as illustrated in Fig. 2.

55 When the discharge is once established and when the current therethrough is maintained substantially constant, the potential drop there across varies with pressure and also with the frequency of the pressure variations in the higher portions of the audibility range. The result of such variations in the sensitiviy of the discharge with frequency is to cause the distortion of the higher notes in the audible-frequency range.

60 After considerable experimental work, as

hereinbefore stated, it was found that it is only the portion of the discharge including the positive column which varies in sensitivity with changes in the frequency of the pressure variations, while the remaining 70 portion of the discharge was found to be substantially insensitive to changes in the frequency of the pressure variations.

Accordingly, apparatus was arranged 75 which made possible the detection of pressure variations in the portion of the discharge between the free end of the positive column 13 and the negative electrode 2. The apparatus comprises a third electrode 14 disposed in the discharge just at the free 80 end of the positive column 13, and a repeater device 14a. The third electrode 14 is provided with a perforation 15' on the order of .014 inch in diameter which is positioned in the path of the discharge.

The alternating component of voltage which is established between the third electrode 14 and the negative electrode 2 in the presence of sound waves may be translated into amplified currents of similar wave form 90 by impressing the same, through conductors 15 and 16, upon the grid and filament elements 17 and 18, respectively, of the repeater device 14a, which includes in addition, a plate element 19.

A condenser 21 having a negligible impedance to currents of sound-wave frequency, is included in the grid conductor 15 and serves to prevent the so-called "quiet voltage drop" in the glow discharge between 100 the third electrode 14 and the negative electrode 2 from operating to block the tube 14a. A grid-leak resistor 22 may be included in shunt relation to the grid and filament elements 17 and 18, respectively, in order to 105 control the intensity of the negative charges which are accumulated on the grid 17.

A plate-filament circuit for the tube 14a includes a source 23 of direct-current energy and a high-impedance resistance coupling 110 device 24. The potential variations, which are established across the resistor 24 when the glow discharge is subjected to pressure variations, as, for instance, those caused by sound waves, may be impressed by conductors 25 and 26 upon the input elements of a second amplifying device (not shown) or other circuit arrangement designed to employ such modulated energy.

115 In order to insure that the discharge will be a glow discharge and will continue to be a glow discharge, and not change into an arc, I find that the source of potential must be high and that a current limiting device must be used. In addition to the specific dimensions already stated herein the following actual constructions are noted. In one specific embodiment of my invention, I employed a source of somewhat more than 4000 volts with a resistance in series between it and 120

the discharge device of approximately one megohm. In another specific embodiment of this invention, I employed a source of 4200 volts, together with a current limiting device which restricted the current to one milliampere. The current limiting device used in this instance was a saturation tube.

A characteristic difference between the glow discharge and the arc is found in the relation of current to voltage. In the arc the current is much greater and the voltage much smaller than in the glow discharge. Another characteristic difference is that with the glow discharge the electrodes are relatively cool, never becoming incandescent, while with an arc the electrodes are hot and the cathode is usually more incandescent than any portion of the arc itself.

During experimental work, it was found that the sensitivity of the glow discharge, as a translating device, decreased as the diameter of the perforation 15' was increased, and that best results were obtained by employing a perforation, the diameter of which was small in comparison to that of the positive column 13. As shown in Fig. 2, the free end of the positive column 13 extends through the perforation 15' without engaging the walls thereof, forming a small tip portion 27. After prolonged operation, the third electrode 14 becomes slightly heated but does not assume the temperature of the glow discharge.

As hereinbefore stated, it was found that still further improved results were obtained by shielding the anode column 13 from the effects of air currents and sound waves, and I have shown, in Figs. 1 and 2, one particular arrangement for carrying this into practice. The arrangement shown comprises a tubular member 28 of insulating material which is supported from one end by the positive electrode 1. The remaining end may carry the third electrode 14.

In view of the foregoing, it is apparent that my invention provides a translating or amplifying device which is characterized by its simplicity of design and operation and by the absence of moving parts. Other advantages will be apparent from a study of the foregoing description.

While I have described my invention as embodied in a particular circuit arrangement having specific values, it is apparent that various changes and modifications may be made therein without departing from the spirit of my invention. I desire, therefore, that only such limitations shall be imposed thereon as are demanded by the prior art or are specifically set forth in the appended claims.

I claim as my invention:

1. In combination, a pair of spaced electrodes, means for maintaining between said electrodes a discharge of the character which

has a dark space and a glowing space means for shielding a predetermined portion only of said discharge from pressure variations in the vicinity of said discharge.

2. A translating device comprising a pair of spaced electrodes, means for maintaining between said electrodes a discharge of the character which has a dark space and glowing spaces, including a positive column, said electrodes being exposed to the pressure of the atmosphere, means for preventing the air immediately adjacent the positive column from departing, said means leaving the air immediately adjacent the remainder of the discharge free to depart.

3. An amplifying device comprising a pair of spaced electrodes, means for maintaining between said electrodes a discharge of the character which has a dark space and glowing spaces including a positive column, said electrodes being open to the air and means for enclosing said positive column in such manner as to shield the same from pressure variations incident to the presence of sound waves said means leaving the other portions of said glow discharge exposed to said variations.

4. In an electrical system, the combination with a pair of electrodes constituting the positive and negative terminals of a discharge device, of means for maintaining between said electrodes a discharge of the character which has a dark space and a glowing space, said discharge including a portion wherein the voltage-current characteristic varies with the frequency of pressure variations thereabout and also including a portion wherein the voltage-current characteristic is substantially independent of the frequency of the pressure variations thereabout and means responsive to variations in the voltage-current characteristic of only the latter portion.

5. In an electrical system, the combination with a pair of electrodes constituting the positive and negative terminals of a discharge device, of means for maintaining between said electrodes a discharge of the character which has a dark space and glowing spaces including a positive column, said electrodes being open to the air and translating means responsive only to variations in the characteristic of only the remaining portions of said discharge.

6. In an electrical system, the combination with a pair of spaced electrodes open to the atmosphere and constituting the positive and negative terminals of a discharge device, of means for maintaining between said electrodes a discharge of the character which has a dark space and a glowing space, a third electrode interposed between said pair of electrodes, and a translating device having an input circuit connected across said third electrode and said negative electrode.

7. In an electrical system, the combination with a pair of spaced electrodes constituting the positive and negative terminals of a discharge device, of means for maintaining between said electrodes a discharge of the character which has a dark space and a glowing space, a third electrode embracing a portion of said discharge and a translating device having input terminals connected to said third electrode and said negative electrode, respectively.
8. In an electrical system, the combination with a pair of spaced electrodes constituting the positive and negative terminals of a discharge device, of means for maintaining a discharge therebetween of the character which has a positive column and a Faraday dark space, a third electrode having a perforation therein positioned in said discharge immediately adjacent to the boundary line between said positive column and said Faraday dark space, and a repeater circuit connected across said third electrode and said negative electrode.
9. In an electrical system, the combination with a pair of spaced electrodes constituting the positive and negative terminals of a discharge device, of means for maintaining a discharge therebetween of the character which has a positive column and a Faraday dark space, a third electrode having a perforation therein disposed in said positive column near the boundary line between said positive column and said Faraday dark space, and a translating device operatively associated with said third electrode and said negative electrode for converting variations in the voltage-current characteristic of the discharge therebetween into amplified current variations.
10. In an electrical system, the combination with a pair of spaced electrodes constituting the positive and negative terminals of a discharge device, of means for maintaining a discharge therebetween of the character which has a positive column and a Faraday dark space, a third electrode disposed intermediate said pair of electrodes near the end of said positive column adjacent to said Faraday dark space, said third electrode having a perforation of relatively small diameter in comparison to that of said positive column, the end of said column extending through said perforation, and a repeater device having its input circuit connected across said third electrode and said negative electrode.
11. A translating device comprising a pair of spaced electrodes, means for maintaining between said electrodes a discharge of the character which has a dark space and glowing spaces including a positive column, said electrodes being open to the air, means for shielding said positive column from the effects of pressure variations in the vicinity

of the discharge, a third electrode interposed between said pair of electrodes near the free end of said positive column and translating means having an input circuit connected across said third electrode and one of said pair of electrodes.

12. In an electrical system, the combination with a pair of electrodes constituting the positive and negative terminals of a discharge device, of means for maintaining between said electrodes a discharge of the character which has a dark space and glowing space including a positive column, said electrodes being open to the air, means for shielding a part, but not all, of said discharge from pressure variations in the immediate vicinity of said discharge, said part including said positive column, a third electrode interposed between said pair of electrodes near the free end of said positive column, said third electrode having a perforation in the path of said discharge, and translating means having an input circuit connected across said third electrode and one of said pair of electrodes.

13. In an electrical system, the combination with a pair of electrodes constituting the positive and negative terminals of a discharge device, of means for maintaining between said electrodes a discharge of the character which has a dark space and glowing spaces including a positive column, said electrodes being open to the air, means for enclosing the space immediately surrounding said positive column to shield said column from pressure variations, a third electrode disposed intermediate said pair of electrodes adjacent to the free end of said positive column, said third electrode having a perforation for receiving said discharge, and translating means having an input circuit connected across said third electrode and one of said pair of electrodes.

14. In an electrical system, the combination with a pair of electrodes constituting the positive and negative terminals of a discharge device, of means for maintaining between said electrodes a discharge of the character which has a dark space and glowing spaces including a positive column, said electrodes being open to the air, means for maintaining the currents through said discharge substantially constant, means for enclosing the space immediately surrounding said positive column to shield said column from pressure variations, a third electrode disposed intermediate said pair of electrodes adjacent to the free end of said positive column, said third electrode having a perforation for receiving said discharge, and translating means having an input circuit connected across said third electrode and one of said pair of electrodes.

15. A sound-wave translating device comprising an apparatus for producing a dis-

charge in the open air and maintaining said discharge of the character which has a dark space and glowing spaces including a positive column, means for minimizing the effect of the positive column upon the characteristics of the discharge in the presence of sound-wave disturbances, and means responsive to the changes in a characteristic of the discharge resulting from said sound waves.

16. A sound-wave translating device comprising an apparatus for producing a discharge in a medium responsive to pressure variation due to sound waves and maintaining said discharge of the character which has a dark space and glowing spaces including a positive column, means responsive to the changes in a characteristic of the discharge resulting from said pressure variations, and means for minimizing the effect

of the positive column upon the characteristics of the discharge in the presence of sound-wave disturbances.

17. In a sound translating device, a pair of spaced electrodes and a source of electro-motive force suitable for maintaining a glow discharge between said electrodes, a portion of the space between said electrodes being open to the sound waves.

18. In a sound translating device, a pair of spaced electrodes and a source of electro-motive force suitable for maintaining a glow discharge between said electrodes, a portion of the space between said electrodes being open to the sound waves and a portion of said space being shielded from them.

In testimony whereof, I have hereunto subscribed my name this 10th day of November, 1922.

PHILLIPS THOMAS.
